United States Patent Office.

ALANSON PIERSON TYLER, OF BOSTON, MASSACHUSETTS.

Design No. 4,052, dated May 17, 1870.

DESIGN FOR A TOY STEAM-ENGINE.

The Schedule referred to in these Letters Patent and making part of the same.

I, ALANSON PIERSON TYLER, of Boston, in the county of Suffolk and State of Massachusetts, have invented a new and original Design for an "Oscillating Steam-Engine Toy," of which the following is a specification.

Figure 1 is a side view.

Figure 2 is an end view, and

Figure 3 is a ground plan of my design.

a is a cylindrical steam-boiler, on the top of which stand two bearings *b b* supporting the shaft *c*.

On the shaft *c* are a fly-wheel, *d*, and a pulley, *e*, between the bearings *b b*.

On the outside of the bearings of the said shaft *c* is, in each end, a crank, *f* and *g*.

The crank *f* is connected, by means of a rod, *h*, to a piston moving in the oscillating steam-cylinder *i*.

The steam-cylinder *i* oscillates around the pin *k*, provided with a spring and tightening-nut.

The crank *g* is also connected, by means of a rod, *l*, to a piston moving up and down in the pump *m*.

The said pump *m* stands firm in the reservoir *n*.

p is a pipe, with a close-fitting cap, whereby the boiler can be filled and emptied. The said cap also serves as a safety-valve when the steam gets up too high pressure.

q is a combined safety-valve and whistle, operating by means of the lever *r*.

The whole is intended as a cheap and durable steam-engine toy for the instruction and amusement of children, and is operated as follows:

Fill the boiler *a* with water, and place it over a warm place; also, fill the reservoir *n* with water. When the water has boiled a short time, the piston and rod *h* in the cylinder *i* will be pressed upward, whereby the crank *f*, wheel *d*, and pulley *e*, are set in a quick circular motion. The crank *g* will also move the rod *l* and piston up and down in the pump *m*, thereby pumping the water up from the reservoir *n*, and letting it flow out through the spout *o* into the reservoir back again, whereby an endless flow of water is obtained.

Having thus described the nature of my design, I claim and wish to secure by Letters Patent—

The design for an oscillating steam-engine toy, as herein fully set forth and described.

A. P. TYLER. [L. S.]
